UNITED STATES PATENT OFFICE.

FRANK A. GALE, OF LOWELL, MASSACHUSETTS.

CONDENSING-ENGINE.

SPECIFICATION forming part of Letters Patent No. 310,575, dated January 13, 1885.

Application filed May 7, 1884. (No model.)

To all whom it may concern:

Be it known that I, FRANK A. GALE, a citizen of the United States, residing at Lowell, in the county of Middlesex and Commonwealth of Massachusetts, have invented certain new and useful Improvements in Condensing-Engines, of which the following is a specification.

My invention relates to an improvement in single-cylinder engines; to means whereby a part of the steam is first exhausted from the cylinder into a heating apparatus, and the remainder of the steam is then exhausted into the condenser in the usual manner, and to means of operating the exhaust-valves.

In the accompanying drawings my improvement is represented as connected with a Corliss engine, Figure 1 being a front elevation of the steam-cylinder and valve-gear; Fig. 2, a central longitudinal section of the steam-cylinder, steam-chest, induction and eduction ports, and exhaust passages and valves, also the piston and piston-rod; Fig. 3, an end elevation of the steam-cylinder, showing also the position of the rocking plates, dash-pots and arms, valve-rods, and extra exhaust-pipe, the first three figures showing the position of the parts represented in them when the forward stroke is nearly completed; Fig. 4, a side elevation of the exhaust-valve detached; Fig. 5, a section on the line X X in Fig. 4; Fig. 6, an end elevation of the engine, showing pipe-connections, heating apparatus, and condenser; Fig. 7, an isometric view of one of the stationary slotted arms which support the spring-studs, and one of said studs; Fig. 8, a vertical section of a spring-stud socket through the slot of the arm.

The steam-cylinder A, piston B, piston-rod B', steam-chest A', induction-ports A² A³, induction-valves C C', their stems e e', and their operating mechanism, including the bell-crank levers F F', dash-pot rods e e', and dash-pots E, (only one being shown,) rocking plate H, eccentric-rod h, crab-claws G G', provided with notches g g', to engage with the studs f f', swiveled on the lower arms of the levers F F', and serving as guides for the rods g² g³, which carry the crab-claws G G', said rods g² g³ being pivoted at one end to the rocking plate H, the knock-offs f² f³, adjustably secured to the hubs of the levers F F', to disengage the crab-claws

from the studs f f', and the springs g⁴ g⁵, which throw the claws G G' upward to engage with the studs f f', may all be of the usual construction and operation.

A⁴ A⁵ are eduction-ports opening into the usual exhaust-chamber, A⁶, the latter being connected by the exhaust-pipe j with the condenser J, in the usual manner. There are other exhaust-pipes, k k', communicating with the eduction-ports and with any suitable heating apparatus, as with the pipes which heat the air of a factory, or with pipes for heating dyes, or for other purposes.

In the drawings, Fig. 6, a pipe, K, is connected in an obvious manner with the exhaust-pipes k k', and this pipe is tapped at desirable intervals to supply radiators k², one of which is shown, and the connection of another, k³. It is not of course new to heat buildings by the exhaust-steam of an engine; but it is believed to be new to exhaust a part of the steam into the heating apparatus and to exhaust the remainder into the condenser. This I accomplish by the exhaust-valves and valve-motion described below, both exhaust-valves being alike.

In place of the usual nearly cylindrical exhaust-valve used in the Corliss engine, I use at each end of the cylinder, on a single valve-stem, L L', a double-seated exhaust-valve, M M', consisting of two half-cylinders, m m', each half-cylinder provided with a longitudinal slot, m², in its flat side, to receive the valve-stem L L', and a steam-passage, m³, formed by cutting away equally the upper edges of said valves or half-cylinders of the same pair, and having a clearance-chamber, m⁴, connected by holes m⁵ through the valve and stem to the steam-passage m³, for the usual purpose of equalizing the steam-pressure on opposite sides of the valve and decreasing the friction on the valve, said clearance-chamber being formed equally in the lower part of the two half-cylinders of the same pair. The valves M M' are partially rotated to allow the steam to be exhausted at the beginning of either the forward or backward stroke into the condenser—that is, when the live steam enters on one side of the piston, the exhaust-valve at the corresponding end of the cylinder is closed entirely, and remains closed until the piston nearly completes that stroke, when it opens to the heat-

ing-pipes, and at or near the completion of the same stroke it closes the passage to the heating-pipes and opens into the condenser-pipe. The valves of course turn in hollow cylindrical seats, substantially as the induction-valves turn.

The mechanism by which the valves are operated is described below.

Turning on the same stud, h^2 , with the rocking plate H is another rocking plate, H', operated independently of the plate H by a separate eccentric-rod and eccentric, like those now used to operate the induction-valves. This plate H' has connected to it by pivots h^3 h^4 the rods n^2 n' , carrying crab-claws N N', just like those commonly used with the induction-valves in the Corliss engines, and above referred to.

Secured to the stems L L', respectively, of the exhaust-valves are the three-armed levers O O', which have each an upper arm, o, a lower arm, o', and a side arm, o².

To the sidearm, o², are pivoted dash-pot rods p p', carrying dash-pots P (only one being shown) at their lower ends. These dash-pots are of the usual construction, each having a guide, p², and air-cock p³, for the usual purpose.

To the lower arm, o', of the three-armed levers are pivoted studs n^2 n^3 , like the studs f f', which serve as guides to the rods n^2 n' , and with which the crab-claws (being thrown upward by the springs) respectively engage to open the eduction-valves to allow the steam from the cylinder to enter the heating-pipes k k'. The time during which the induction-valves remain open is controlled by the governor operating the connecting-rods II' to rock the levers i i', the hubs i² i³ of which have slight projections or knock-offs f² f³ fixed on them, as is well understood, and turn freely on the valve-stem to bring the knock-offs at suitable times in contact with the upper arms of the crab-claws G G', and thereby disengage the lower arms of said claws from the studs f f', whereupon the weight of the dash-pots E turns the lever and closes the induction-valves. The exhaust or eduction valves are alternately turned to close the heating-pipes and open the condenser-pipes by knock-offs q q', which, although adjustable, operate uniformly. The knock-offs q q' are slotted pieces, having projections q² q³, secured by screws passing through the slot q⁴ thereof into the hub of the lever O, which projections strike the upper arms of the crab-claws N N' and disengage their lower arms from the studs n^2 n^3 , the weight of the dash-pots P pulling down the side arm, o², and rotating the exhaust-valves to open them into the condenser-pipes, only one exhaust-valve, of course, being open at the same time. The exhaust-ports are closed (one at a time) by the long arms of the bent pawls R R' striking the inside of the upper arms, o, of the levers, said pawls being pivoted on pawl-rods r r', which are pivoted at their inner ends by studs, one of which, u, is shown, to the back rocking plate, H, and slide

in the stud pivoted to the upper arms, o, just as the studs are pivoted to the lower arm, o'. The long arms r² r³ of the pawls are thrown down by the springs r⁴ r⁵, but are prevented from falling below the pawl-rods by stops S S', secured to said pawl-rods, or by straddling said rods. At the same time that either pawl (for illustration, say R) pushes against the corresponding lever, O, and closes the corresponding exhaust-valve, M, the side arm, o², of the same lever, O, partially raises the dash-pot P, connected to said short arm. When either pawl is drawn back from the corresponding lever, the short arm of the pawl strikes against the stud T or T', as the case may be, and raises the long arm of the pawl above the top of the lever, so that said lever may swing under it and allow the dash-pot to fall, the dash-pot having been raised in the meantime. The pawl is raised, as above described, just as the knock-off q q' hits the upper arm of the crab-claw N N'. The stud T T' is beveled on top away from the outer side, and provided with an enlarged head, t. The shank t' of the stud is surrounded by a spiral spring, t², which is compressed between the head of the stud and a shoulder, v, in the stud-holder V. The shank of the stud-holder reaches through a slot in the arm W or W', which is secured to the valve-stem guide or bearing, and is held in place by an external shoulder, v', of the holder, resting on the top of the arm W, and a nut, v, screwed on the threaded lower end of said holder up against said arms W W'. The stud T is prevented from jumping out of the holder by a nut, t², screwed on its threaded lower end. The pawl moves in over the top of the spring-stud far enough to allow the long arm of the same to drop inside of the stud when the dash-pot P is down. When the pawl moves outward again partially raising the dash-pot P, the beveled end of the short arm of the pawl slides over the bevel on the spring-stud and forces the latter down out of its way, the spring-stud rising again when the pawl has passed entirely over it.

I claim as my invention—

1. In an engine, the combination of the cylinder having an eduction-port, two exhaust-steam-conducting pipes, a two-way valve adapted to connect either of said pipes with said eduction-port, and automatic means, substantially as described, for operating said valve, as and for the purpose specified.

2. The combination of the rocking plates, the pawl-rod, and the bent pawl pivoted thereto, the spring-stud, the three-armed lever provided with pivoted guide-studs, the dash-pot connected to said lever, the crab-claw and its rod, the knock-off, and the two-way valve, as and for the purpose specified.

FRANK A. GALE.
